UNITED STATES PATENT OFFICE

NAPOLEON R. THIBERT, OF WORCESTER, MASSACHUSETTS

LIQUID FUEL BURNER

Application filed December 8, 1930. Serial No. 500,880.

This invention relates to improvements in liquid fuel burners adapted particularly to be set in domestic stoves and ranges without necessitating material changes therein where-
5 by they may be operated by liquid fuel instead of other forms of fuel.

This invention further relates to improvements and additions in and to my liquid fuel burner set forth and described in my application for Letters Patent filed in the United States Patent Office on or about September 13, 1930 and given the Serial Number 481,695.

The principal objects of the invention are to provide an improved cap or sleeve for the vaporizing chamber of a liquid fuel burner of this character which will be resistant to the heat of combustion and will not readily burn through by the action of said heat but will be long lived and more efficient in its action than prior art constructions and to provide improved means to decrease carbonizing effects in the vaporizing chamber of said burners whereby all of the advantages of my burner of the aforesaid application may be obtained and carried out with added efficiency and economy.

Other objects of the invention are to provide improved means of preventing deterioration and burning through of the walls of the sleeve or cap of the vaporizing chamber, for preventing air drafts into said chamber with consequent carbonizing effects, for breaking up and removing carbon deposits from said chamber and for increasing the vaporizing efficiency of the burner.

Another object of the invention is to provide an improved cover for the sleeve or cap of the vaporizing chamber which will be economical to produce and which will increase the vaporizing efficiency.

Other objects and advantages of the invention will become apparent from the following description taken in conjunction with the accompanying drawing. It will be apparent that many changes in the arrangement of parts and details of construction can be made without departing from the spirit of the invention as expressed in the accompanying claims. I, therefore, do not wish to be limited to the exact arrangement shown

and described as the preferred form only has been shown and described by way of illustration.

Referring to the drawing:

Fig. I is a longitudinal cross section 55 through a liquid fuel burner embodying my invention;

Fig. II is a top plan view of the top of said burner, and

Fig. III is a perspective view of the cap 100 or sleeve of the vaporizing chamber with the top thereof separated and slightly removed therefrom.

In liquid fuel burners of the type described in my application aforesaid it has 65 been found from experience that the cap or sleeve of the vaporizing chamber has a tendency to burn through from the torch like action directed against certain parts thereof during combustion. These sleeves or caps 70 have previously been made of cast iron. Such sleeves soon become pitted and perforated from the action of the heat and flame and have to be thrown away. Air will seep in through the perforations and cause added 75 carbon deposits in the interior of the vaporizing chamber. This deterioration of the sleeves has been not only a source of annoyance but has had a detrimental effect upon

the sales of said burners as the consumer 80 often found his burner inoperable and replacements could not be made without loss of time, use of the burner, and considerable trouble in going to the agent or the manufacturer for a new part. Where such cast 85 iron sleeves were used there was also a seam or joint at the place where the sleeve fitted on the vaporizing chamber which joint caused an air leak and allowed carbon deposits to 90

be formed in the sleeve and vaporizing chamber. It is therefore one of the prime objects of my invention to remove these objections and provide a simple and cheap 95 sleeve for the vaporizing chamber that will not pit or burn in holes and will last indefinitely and which will also eliminate the air current at the joint of the sleeve and vaporizing chamber; and which will also be more 100 efficient in its vaporizing action and will as-

sist in removing carbon deposits from the vaporizing chamber.

Referring to the drawing in which corresponding numerals denote corresponding parts throughout: The sleeve or cap for the vaporizing chamber of the invention is shown applied to a liquid fuel burner of the type described in my aforesaid application. This burner broadly comprises a burner base 1, preferably circular in shape, having the annular combustion grooves or chambers 2, having the shouldered ledges 3 supporting the combustion rings 4 which are provided with the perforations 5. The combustion grooves 2 are connected with the fuel conduits or passageways 6. These conduits connect the outer combustion grooves 2 with the central vaporizing chamber 7.

The combustion rings 4 are annular in shape and fit the shouldered ledges 3 on the base 1. They form between them the combustion chambers 11 and 12, being in direct communication with the combustion grooves 2. The walls of the rings 4 are perforated at 5 to provide means for heat circulation. Over the top of the rings 4 is the cover plate 13.

In the central portion of the burner is the vaporizing chamber 7. This chamber comprises a chamber cap or sleeve 17 having a separable cover or top 18. The sleeve 17 is made of rolled sheet material having a high resistance to heat such as chromium steel. The sheet stock is rolled into a tube and butted on the line 19 having a seam strap 20 welded or otherwise secured over the seam. The cover 18 is also of the same material and so formed as to fit loosely upon the top of the tube and to be retained there by gravity. It will be noted that the seam strap 20 extends only partially of the seam 19 for a reason to be explained later. The bottom of the tube is scalloped to form the scallops 21 for a purpose to be described later.

The tube or sleeve 17 fits snugly into the well 22 of the vaporizing chamber 7 to preferably form an air tight union therewith, the end of the strap 20 resting on the top thereof. The bottom of the sleeve 17 rests on the bottom of the vaporizing chamber. If desired the strap 20 may be placed on the inside of the sleeve 17 and extend from top to bottom thereof making it air tight along the whole distance of the seam 19. The scallops 21 permit the liquid fuel to pass along the conduits 6. These scalloped edges also provide a simple and efficient means by which the carbon deposits in the vaporizing chamber may be broken up and loosened by simply turning the tube. The loose top 18 has been found to act efficiently when resting loosely upon the top of the sleeve 17, due to the fact that unless the top 18 is securely held down upon the top of the sleeve, a slight opening will be formed between the upper

edge of the sleeve and the top 18, sufficient to permit passage of air or vapor thereby. The difference in pressures which will occur between the chamber 7 and the space inside of the inner combustion tube 14 will facilitate this "breathing" action. If desired it may be perforated for a breather opening and it then may be securely fastened to the sleeve. If desired a baffle plate or regulator may be placed within the sleeve as described in my aforesaid application.

The operation of the burner is the same as that described in my aforesaid application. The burner may be supported by a stand if desired or in any preferred way.

The action of the vaporizing chamber has been considerably improved by the addition of my heat resisting sleeve 17. The chromium sheet steel does not become pitted and perforated from the action of the heat. It resists without apparent deterioration the intense heat to which it is subjected. The sleeve extends through the well 22 to the bottom of the vaporizing chamber, the air joint at the top of the well is avoided and there is hence less tendency to carbonize in its neighborhood. It has been found that the vaporizing tendency is increased as the length of the sleeve 17 is increased, hence by proper selection of the length of the sleeve the vaporizing effect may be determined.

The vaporizing cap or sleeve 17 is not only heat resisting in its nature but is also non-oxidizing as well whereby it remains clean and practically free from deposits and carbonized collections. The sleeve 17 also protects the walls 22 of the well and prevents the pitting and burning out of this portion of the base, thus prolonging the life of the burner and insuring a higher vaporizing efficiency in the vaporizing chamber and in the sleeve thereof.

From the foregoing description it will be seen that I have provided simple, efficient and economical means for obtaining all the objects and advantages of the invention.

Having described my invention I claim:

1. In a burner of the character described, a base member having a fuel channel, a combustion chamber above said channel comprising upstanding perforated walls, said base member having a well, forming a vaporizing chamber, and a vaporizing sleeve composed of material having higher heat resistance than cast iron spaced from and independent of said combustion chamber and extending from the vaporizing chamber, up within and beyond the walls of said well, to a location adjacent said combustion chamber for heating thereby, means to supply liquid fuel to said vaporizing chamber, and means establishing communication between said chamber and said fuel channel, comprising a conduit positioned to form an additional vaporizing chamber.

2. In a burner of the character described,

5 a base member having a fuel channel, a combustion chamber above said channel comprising upstanding perforated walls, said base member having a well, forming a vaporizing chamber, and a vaporizing sleeve composed of material having higher heat resistance than cast iron spaced from and independent of said combustion chamber and extending from the vaporizing chamber, up within and beyond the walls of said well, to a location adjacent 70
10 said combustion chamber for heating thereby, means to supply liquid fuel to said vaporizing chamber, and means establishing communication between said chamber and said fuel channel, comprising a conduit positioned to form an additional vaporizing chamber, the level of the bottom of said conduit being located below the level 75
15 of said well and below said channel.

20 3. In a burner of the character described, a base member having a fuel channel, a combustion chamber above said channel comprising upstanding perforated walls, said base member having a well, forming a vaporizing chamber, and a vaporizing sleeve composed of chromium steel, spaced from and independent of said combustion chamber and extending from the vaporizing chamber, up within and beyond the walls of said well, to a location adjacent 80
25 said combustion chamber for heating thereby, said sleeve having a removable cover across its upper end, means to supply liquid fuel to said vaporizing chamber, and means establishing communication between 85
30 said chamber and said fuel channel, comprising a conduit positioned to form an additional vaporizing chamber.

4. In a burner of the character described, a base member having a fuel channel, a combustion chamber above said channel comprising upstanding perforated walls, said base member having a well, forming a vaporizing chamber, and a vaporizing sleeve composed of material having higher heat resistance than cast iron spaced from and independent of said combustion chamber and extending from the bottom wall of the vaporizing chamber, up within and beyond the walls of said well, to a location adjacent 90
45 said combustion chamber for heating thereby, a portion of the wall of the sleeve within the vaporizing chamber being cut through, means to supply liquid fuel to said vaporizing chamber, and means establishing communication 95
50 between said chamber and said fuel channel and through said cutout portion, comprising a conduit positioned to form an additional vaporizing chamber.

55 5. In a burner of the character described, a base member having a fuel channel, a combustion chamber above said channel comprising upstanding perforated walls, said base member having a well, forming a vaporizing chamber, and a vaporizing sleeve composed of material having higher heat resistance 100
60

than cast iron spaced from and independent of said combustion chamber and extending from the bottom wall of the vaporizing chamber, up within and beyond the walls of said well, to a location adjacent said combustion 70
65 chamber for heating thereby, a portion of the wall of the sleeve within the vaporizing chamber being cut through, means to supply liquid fuel to said vaporizing chamber, and means establishing communication between 75
70 said chamber and said fuel channel and through said cutout portion, comprising a conduit positioned to form an additional vaporizing chamber, the level of the bottom of said conduit being located below the level 80
75 of said well and below said channel.

80 6. In a burner of the character described, a base member having a fuel channel, a combustion chamber above said channel comprising upstanding perforated walls, said base member having a well, forming a vaporizing chamber, and a vaporizing sleeve composed of material having higher heat resistance than cast iron spaced from and independent of said combustion chamber and extending 85
85 from the bottom wall of the vaporizing chamber, up within and beyond the walls of said well, to a location adjacent said combustion chamber for heating thereby, a portion of the wall of the sleeve within the vaporizing chamber being cut through, said sleeve having a cover of the same material as the sleeve across its upper end, means to supply liquid fuel to said vaporizing chamber, and means establishing communication between said 90
90 chamber and said fuel channel and through said cutout portion, comprising a conduit positioned to form an additional vaporizing chamber.

95 7. In a burner of the character described, a base member having a fuel channel, a combustion chamber above said channel comprising upstanding perforated walls, said base member having a tubular well, forming a vaporizing chamber, and a removable tubular vaporizing sleeve composed of material having higher heat resistance than cast iron spaced from and independent of said combustion chamber and extending from the bottom wall of the vaporizing chamber, up within and beyond the walls of said well, to a location adjacent said combustion chamber for heating thereby, the walls of the well and sleeve forming an air tight joint, a portion 100
100 of the wall of the sleeve within the vaporizing chamber being cut through, means to supply liquid fuel to said vaporizing chamber, and means establishing communication between said chamber and said fuel channel and through said cutout portion, comprising a conduit positioned to form an additional vaporizing chamber.

110 8. In a burner of the character described, a base member having a fuel channel, a combustion chamber above said channel comprising 115
115

- ing upstanding perforated walls, said base member having a tubular well, forming a vaporizing chamber, and a removable tubular vaporizing sleeve composed of material having higher heat resistance than cast iron spaced from and independent of said combustion chamber and extending from the vaporizing chamber, up within and beyond the walls of said well, to a location adjacent said combustion chamber for heating thereby, the walls of the well and sleeve forming an air tight joint, said sleeve being provided with a breather member adjacent its top, means to supply liquid fuel to said vaporizing chamber, and means establishing communication between said chamber and said fuel channel, comprising a conduit positioned to form an additional vaporizing chamber.
9. In a burner of the character described, a base member having a fuel channel, a combustion chamber above said channel comprising upstanding perforated walls, said base member having a tubular well, forming a vaporizing chamber, and a removable tubular vaporizing sleeve composed of material having higher heat resistance than cast iron spaced from and independent of said combustion chamber and extending from the bottom wall of the vaporizing chamber, up within and beyond the walls of said well, to a location adjacent said combustion chamber for heating thereby, said sheet sleeve being shaped to closely fit the walls of the well and form an air tight joint therewith, and the longitudinal edges of the sheet being secured together and sealed to form an air tight joint longitudinally thereof, a portion of the wall of the sleeve within the vaporizing chamber being cut through, means to supply liquid fuel to said vaporizing chamber, and means establishing communication between said chamber and said fuel channel and through said cutout portion, comprising a conduit positioned to form an additional vaporizing chamber.
10. In a burner of the character described, a base member having a fuel channel, a combustion chamber above said channel comprising upstanding perforated walls, said base member having a well, forming a vaporizing chamber, and a vaporizing sleeve composed of sheet material having higher heat resistance than cast iron spaced from and independent of said combustion chamber and extending from the vaporizing chamber, up within and beyond the walls of said well, to a location adjacent said combustion chamber for heating thereby, said sheet sleeve being shaped to closely fit the walls of the well and form an air tight joint therewith and the longitudinal edges of the sheet being secured together and sealed to form an air tight joint longitudinally thereof, said sleeve being provided with a breather member adjacent its top, means to supply liquid fuel to said vaporizing chamber, and means establishing communication between said chamber and said fuel channel, comprising a conduit positioned to form an additional vaporizing chamber.
11. In a burner of the character described, a base member having a fuel channel, a combustion chamber above said channel comprising upstanding perforated walls, said base member having a well, forming a vaporizing chamber, and a vaporizing sleeve composed of sheet material having higher heat resistance than cast iron spaced from and independent of said combustion chamber and extending from the bottom wall of the vaporizing chamber, up within and beyond the walls of said well, to a location adjacent said combustion chamber for heating thereby, said sheet sleeve being shaped to closely fit the walls of the well and form an air tight joint therewith, and the longitudinal edges of the sheet being secured together and sealed to form an air tight joint longitudinally thereof, a portion of the wall of the sleeve within the vaporizing chamber being cut through, means to supply liquid fuel to said vaporizing chamber, and means establishing communication between said chamber and said fuel channel and through said cutout portion, comprising a conduit positioned to form an additional vaporizing chamber.
12. In a burner of the character described, a base member having a fuel channel, a combustion chamber above said channel comprising upstanding perforated walls, said base member having a well, forming a vaporizing chamber, and a vaporizing sleeve composed of sheet material having higher heat resistance than cast iron spaced from and independent of said combustion chamber and extending from the vaporizing chamber, up within and beyond the walls of said well, to a location adjacent said combustion chamber for heating thereby, said sheet sleeve being shaped to closely fit the walls of the well and form an air tight joint therewith and the longitudinal edges of the sheet being secured together and sealed to form an air tight joint longitudinally thereof, said sleeve being provided with a breather member adjacent its top, means to supply liquid fuel to said vaporizing chamber, and means establishing communication between said chamber and said fuel channel, comprising a conduit positioned to form an additional vaporizing chamber.

NAPOLEON R. THIBERT.
